UNITED STATES PATENT OFFICE.

WILLIAM W. BURESCH, OF BALTIMORE, MARYLAND.

BOTTLE-CAPPING TOOL.

1,353,718.

Specification of Letters Patent. Patented Sept. 21, 1920.

Application filed July 11, 1919. Serial No. 310,171.

To all whom it may concern:

Be it known that I, WILLIAM W. BURESCH, a citizen of the United States, residing at Baltimore, in the State of Maryland, 5 have invented certain new and useful Improvements in Bottle-Capping Tools, of which the following is a specification.

This invention relates to improvements in devices for applying crimped metal caps to 10 bottles. The particular purpose of the invention is to provide a device by means of which crimped caps which have been removed from bottles can be re-applied in a secure and air-tight manner. In carrying 15 out the invention, I provide three arcuate crimping members, which may be of the same size and made in the same die, these members, when brought together, forming a ring adapted to encircle a bottle cap and 20 having internal teeth or serrations adapted to fit the indentations in the crimped portion of a bottle cap. Two handles are pivotally connected to one of the crimping members or jaws, and the other members or jaws, 25 having internal teeth or serrations adapted to fit the indentations in the crimped portion of a bottle cap. Two handles are pivotally connected to one of the crimping members or jaws, and the other members or jaws, 30 are each separately connected to said handles, preferably in a rigid manner, and by pressing the handles toward one another, the jaws may be made to press a used bottle cap into its original shape around the bead 35 on the bottle. A spring connects the pivoted handles together, and this spring extends across the opening between the jaws, at a fixed height above the jaws, the arrangement being such that when a cap is 40 placed upon a bottle and the jaws are pressed down over the sides of the cap, the spring will hold the jaws around the cap and also serve as a stop to position the jaw teeth in the indentations in the cap. For 45 convenience, also, in forcing the cap over the bead on the bottle, I provide an additional handle, projecting oppositely from the aforesaid pair of handles, so that the device may be readily grasped in both hands.

45 In the accompanying drawing,

Figure 1 is a top plan view of the crimping device, showing the jaws partly opened to receive the cap;

Fig. 2 is a section on the line 2—2 of Fig. 50 1; and,

Fig. 3 is a perspective view of one of the pivotal handles with attached jaw.

Referring to the drawing, *a*, *b*, and *c*, indicate three arcuate jaws of the same form

and size and which may be cut from sheet 55 metal, in the same dies. These jaws are provided with inwardly projecting teeth 1, suitably spaced to engage the indentations in bottle caps such as have been formed by machinery and applied to bottles containing 60 beverages and other liquids. The jaws *b* and *c* are separately secured to handles 2 and 3, respectively, and these handles are pivotally connected to the jaw *a* at the pivotal points 4 and 5. The jaws *b* and *c* are 65 preferably secured in a rigid manner to the handles 2 and 3, and in the drawing they are shown connected to the handles by rivets 6 and studs 7. A helical spring 8 is connected to the studs 7 and tends to draw the 70 pair of pivoted handles toward one another, to close the jaws. This spring passes over the opening between the jaws, as shown. When a crimped cap is to be re-applied to a 75 bottle, the cap is placed over the bottle mouth and the jaws of the capping tool are brought down over the cap until the spring 8 engages the top of the cap. The teeth on the jaws will then be in position to engage the indentations in the side wall of the cap. 80 The spring serves as a stop to position the jaws and to prevent them from going below the cap, and also serves to automatically hold the jaws in engagement with the cap. 85 For convenience in pressing the cap on to the bottle, I provide a handle 9, which is secured to the jaw *a* and projects in the direction opposite to that of the handles 2 and 3, so that the operator may grasp the device 90 with both hands. This handle 9 may be omitted if desired.

It is believed the construction and operation of the device will be clear from the above description without further explanation.

95

What I claim is:

A device for attaching crimped caps to bottles comprising three arcuate crimping jaws adapted to encircle a cap, a pair of handles both pivotally connected to one jaw 100 and each having one of the other jaws separately secured to it, and a spring for holding said jaws in closed position, said spring extending over the opening between the jaws.

105

In testimony whereof I affix my signature.

WILLIAM W. BURESCH.
